UNITED STATES PATENT OFFICE.

HARRY D. CLINTON, OF JOHNSON CITY, NEW YORK.

TUFT-YARN SPOOL FOR LOOMS.

Application filed September 28, 1922. Serial No. 591,113.

To all whom it may concern:

Be it known that I, HARRY D. CLINTON, a citizen of the United States, residing at Johnson City, in the county of Broome and State of New York, have invented certain new and useful Improvements in Tuft-Yarn Spools for Looms; and I do hereby declare the following to be a full, clear, and exact description of the invention, such as will enable others skilled in the art to which it appertains to make and use the same.

This invention relates to spools and more particularly to the heads of spools used on tuft yarn frames and carriers in wide or narrow looms as used especially in the manufacture of Axminster carpets and rugs in which a strong, durable and non-breakable spool and head are essential to the production of an even, smooth, uniform and regular weave in the fabric.

Spools heretofore used in the manufacture of Axminster carpets and rugs, the value of which depends largely upon the fineness and evenness of texture, have been made either of wood or steel, neither of which, however, has proven satisfactory. Spools with wooden heads are not sufficiently strong to endure the severe strain, wear and friction necessarily placed upon them, and therefore split or become so badly dented and worn after slight use as to permit the head of the spool to be caught and tripped by the spring tension regulator bearing against the outer peripheral edge thereof, causing what is known as a "low row" or imperfection in the rug, or else breaking the yarn in two, thus frequently making it necessary to stop the loom to accomplish repair and replacement, with incident loss of time and expense. Steel

heads and steel spools are likewise impracticable, since the metal becomes heated and expands, causing the spool to bind or warp, producing unevenness in the texture of the rug and necessitating frequent replacement.

The weight of a steel spool is also an additional objection. Considerable time is consequently lost through present day devices, and much otherwise avoidable expense is involved in the manufacture of these carpets.

It has also been proposed to construct spool heads composed of disks of re-enforced vulcanized fibre for use in the manufacture of fabrics of silk, cotton, wool and the like, and I therefore make no broad claim to a vulcanized fibre head per se.

The object of this invention is to over-

come the objections above noted, and to provide a tuft yarn spool with a hard, non-breakable head which will not wear away, warp, become dented nor split, and which will last as long as the loom itself, permitting an uninterrupted, even, smooth, uniform and regular weave of the carpet, and which in addition will be light, durable and strong, impervious to heat caused by friction, thus supplying to the market and to manufacturers, a dependable spool which will greatly increase the efficiency of carpet weaving machines and reduce the expense heretofore involved in the manufacture of Axminster carpets and rugs.

Another object of my invention is to provide a spool of the character referred to, in which the head of vulcanized hard fibre is so securely fastened to the soft-wood barrel or loom of the spool that it may not become loosened nor removed therefrom without breaking the spool apart.

My invention essentially differs from ordinary spool devices, inasmuch as it is designed especially as a tuft yarn spool peculiarly adapted for use in the manufacture of Axminster carpets and rugs, in which the head, upon which the value of production so largely depends, comprises composite materials treated in such manner as to produce a radical, new and requisite improvement over devices heretofore known and employed in the carpet industry.

My invention will first be hereinafter more particularly described, with reference to the accompanying drawings, which are to be taken as a part of this specification and then pointed out in the claims at the end of the description.

In said drawings, Fig. 1 is a longitudinal elevation of my improved tuft yarn spool;

Fig. 2 is a longitudinal sectional elevation of broken away end portions of the spool;

Fig. 3 is a sectional side elevation taken on the line 3-3 of Fig. 2;

Fig. 4 is a side elevation of the tapered fastener plug; and

Fig. 5 is a sectional view of one end of the spool barrel and a fragment of the head in position for assembling.

Referring to the drawings in which like reference numerals are used to denote corresponding parts throughout the several views, 1 denotes an ordinary soft-wood barrel of a tuft yarn spool, opposite ends of the

barrel being provided with sockets or recesses 2 about two inches in depth, the outermost portions or extremities of the barrel being counter bored to form annular peripheral projections or flanges 3.

To the opposite ends of the barrel 1 are secured hard vulcanized fibre spool heads 4, preferably composed of a multiplicity of very thin layers of cloth, pressed and vulcanized together by the use of zinc, said heads being provided with annular grooves 5 adapted to register with and snugly receive the annular flanges 3 provided on opposite ends of the soft-wood barrel 1, cement or glue being utilized to hold the two elements together, such mode of attachment positively preventing the soft-wood barrel from splitting when a lateral strain is applied to the vulcanized fibre head. Lateral strains on spools as heretofore constructed invariably cause the soft-wood barrels to split, which is a difficulty continuously experienced by carpet manufacturers, and the main objection to the ordinary spools commonly used. The head 4 is also provided with a central tapering or frusto-conical orifice 6, the inner circumferential edge thereof registering with the outer circumferential edge of the socket or recess 2 in the barrel 1.

A wooden fastening plug comprising a body portion 7 having a tapered or frusto-conical head 8 adapting it to fit snugly within the tapering or frusto-conical socket or recess formed by the union of the head 4 with the barrel 1, bringing the central orifice 6 into registration with the socket 2, is coated with cement or glue and driven into the socket 2, its tapered head 8 seating within the tapering orifice 6 in the head 4, thus firmly and securely binding the head 4 to the barrel 1, as illustrated in Fig. 2. The plug is preferably about two inches in length, presenting a much larger glue-coated surface area to the inner wall surface of the socket 2 than is usual in spools of ordinary construction, which fact in connection with the tapered head 8 preventing outward movement of the spool head 4, so firmly secures the spool head to the barrel as to render subsequent separation impossible unless the spool is broken apart.

The fastening plug secured in one end of the spool 1 is provided with a central, longitudinal bore 9, adapting a stationary, projecting guide or axis pin 10 to be inserted within the plug and glued or otherwise secured in place. The fastening plug secured in the opposite end of the spool 1, is likewise provided with a longitudinal central bore, the innermost end being counter bored to larger diameter as illustrated in Fig. 2, to accommodate a retractable plunger or guide pin 11, carrying an ordinary encircling coiled spring 12. The retractable pin

11 is shouldered near its innermost end, the spring 12 being interposed between said shoulder and the terminus of the socket 2, which may be likewise counter bored to proper diameter to accommodate one end 70 of the spring, said spring tensionably holding the plunger 11 normally extended through the spool head. Since the spool guides or pins 10 and 11 are thus carried within the fastening plugs, which are essentially a part of the spool head, it may be said that such elements are self contained within the hard vulcanized fibre head. 75

From the foregoing, it will be readily understood that I have provided a novel and highly useful improvement in tuft yarn spools, and that my invention removes all the objectionable features involved in spools of ordinary construction, supplying particularly to manufacturers of Axminster carpets and rugs, a dependable, non-breakable, even running spool, which is so essential to the peculiar needs of such industry. 80

Having thus described my invention, what I claim as new and desire to secure by Letters Patent of the United States is:

1. A tuft yarn spool comprising a barrel of wood having oblong sockets formed in the ends thereof and projections or flanges extending around the outer ends of said sockets, and heads of hard vulcanized fibre having central openings therein of frusto-conical form, and annular grooves in their confronting faces in which said flanges are seated, and means whereby said heads are rigidly and permanently secured to said barrel, so as to form a practically integral structure, without using bolts or screws; said means consisting of wooden plugs inserted through the openings in said heads and extending into said sockets and having their outer ends of frusto-conical form to closely fit said openings; said plugs being secured in said sockets by an adhesive substance applied before inserting them in the 100 sockets. 105

2. A tuft yarn spool comprising a wooden barrel having hard vulcanized fibre heads; said barrel having oblong sockets in the ends thereof and annular projections or flanges overhanging the outer ends of said sockets, and said heads having annular grooves in their confronting faces in which said flanges are seated and also having central openings therein of frusto-conical form, 115 and means for rigidly and permanently securing said barrel and heads together, so as to form a practically integral structure, without using bolts or screws; said means consisting of wooden plugs inserted through the openings in said heads and having oblong shanks inserted in said sockets, the outer ends of said plugs being of frusto-conical form to closely fit said frusto-conical openings and hold the heads tightly 120 125 130

against the ends of the barrel; an adhesive substance being applied to said plugs for securing them in said sockets.

3. A tuft yarn spool comprising a wooden barrel having a socket in each end thereof and an annular peripheral projection or flange overhanging the outer end of the socket; heads composed of hard vulcanized fibre fixed on the ends of said barrel, each 10 head having a central opening therein of frusto-conical form flaring outwardly and an annular groove on its inner side surrounding the central opening, said flanges being inserted in said grooves and the end 15 portions of the barrel encircled by said flanges abutting against the inner sides of the hard fibre heads, and means for rigidly and permanently securing said barrel and heads together, so as to form a practically 20 integral structure; said means consisting of wooden plugs having end portions of frusto-conical form fitted in the correspondingly shaped openings in said heads and having their shanks protruding through said openings 25 into said sockets; an adhesive substance being applied for securing said plugs in said sockets.

4. A tuft yarn spool comprising a wooden barrel having hard vulcanized fibre heads; 30 said barrel having oblong sockets in the ends thereof and annular projections or flanges overhanging the outer ends of said sockets, and said heads having annular grooves in their confronting faces in which 35 said flanges are seated and also having central openings therein of frusto-conical form, and means for rigidly and permanently securing said barrel and heads together, so as to form a practically integral structure, 40 without using bolts or screws; said means consisting of wooden plugs inserted through the openings in said heads and having oblong shanks inserted in said sockets, the outer ends of said plugs being of frusto-conical 45 form to closely fit said frusto-conical openings and hold the heads tightly against the ends of the barrel; an adhesive substance being applied to said plugs for securing them in said sockets; said plugs being axially 50 bored and having pintles inserted therein, one pintle being forced outwardly by a spring acting thereon to adapt it to yield to opposed pressure.

5. A tuft yarn spool comprising a comparatively soft wooden barrel having extended annular flanges and longitudinally disposed sockets formed in either end thereof, heads composed of hard vulcanized and non-resilient fibre, having annular grooves formed in their opposing faces and provided with central frusto-conical orifices, the inner circumferential edges of said orifices registering with the outer circumferential edges of said sockets, the extended annular flanges on said barrel being adapted to fit 60 within the annular grooves in said heads and glued therein, wooden fastener plugs comprising a body portion having a frusto-conical head adapted to fit within the tapering sockets formed by the union of said 65 heads with said barrel and glue-coated to rigidly secure the heads to the barrel, said fastener plugs being longitudinally bored to accommodate spool guide pins inserted therein and projecting through said heads, 70 substantially as described.

6. A tuft yarn spool comprising a comparatively soft wooden barrel having extended annular flanges and longitudinally disposed sockets formed in the ends thereof, 80 heads of hard vulcanized and non-resilient fibre having annular grooves formed in their opposing faces provided with central frusto-conical orifices, the inner circumferential edges of said orifices registering 85 with the outer circumferential edges of said sockets, the annular flanges on said barrel adapted to fit within the annular grooves in said heads and glued therein, wooden fastener plugs comprising body portions having frusto-conical heads adapted to fit within the tapering sockets formed by the union 90 of said heads with said barrel and glue-coated to rigidly secure the heads to the barrel, said fastener plugs being longitudinally bored and partially counter bored to larger diameter, retractable spool guide pins and tension springs fitted respectively within 95 said bores and counter bores in the fastener plugs, substantially as described.

In testimony whereof I affix my signature in the presence of two witnesses.
